UNITED STATES PATENT OFFICE.

ISRAEL SHOUDY, JR., AND CHARLES ATHERTON, OF PAW PAW GROVE,
ILL.; SAID ATHERTON ASSIGNOR OF ONE-THIRD TO SAID SHOUDY.

DUMPING-CAR.

SPECIFICATION forming part of Letters Patent No. 268,299, dated November 28, 1882.

Application filed September 21, 1882. (No model.)

To all whom it may concern:

Be it known that we, ISRAEL SHOUDY, Jr., and CHARLES ATHERTON, of Paw Paw Grove, in the county of Lee and State of Illinois, have 5 invented certain new and useful Improvements in Railroad Dumping-Cars; and we do hereby declare that the following is a full, clear, and exact description of the invention, which will enable others skilled in the art to which it applies to make and use the same, reference being had to the accompanying drawings, which form a part of this specification, and in which—

Figure 1 is a bottom view of our improved dumping-car. Fig. 2 is a longitudinal vertical 15 section, and Fig. 3 is a cross-section, of the same.

Similar letters of reference indicate corresponding parts in all the figures.

Our invention has relation to drop-bottom 20 dumping-cars; and it consists in the improved construction, combination, and arrangement of parts of the same, as hereinafter more fully described and claimed, said improvement having for its object to combine simplicity of construction and operation with great strength 25 and solidity of its parts.

In the accompanying drawings, the letters A A indicate the side sills of the car-body, which is mounted in the usual manner on 30 trucks. In bearings b b in the cross-beams B B are hung two bars, C C, parallel to the side sills, A A, and provided at both ends with eccentric disks or blocks D D. These eccentricities support the bottom, which consists of two 35 parts, E E, inclined toward the middle of the car, and either pivoted in the end sills or cross-beams, B, or hinged to the side sills, A. To the ends of bars C C are secured levers F, pass-

ing up through slots f in the platform G of the car, where they may be held in position adjustably by a cam-rack or otherwise, so as to be readily released when desired. By moving each pair of levers toward or from each other the eccentricities will support or release the sides or flaps of the drop-bottom, and the eccentricities 45 being cut off obliquely on the sides facing the flap when down, they will form a rest for them when in that position, as shown in Fig. 3. It will also be observed that where the eccentricities are in this position their swell or rounded side 50 impinges upon or butts against their appropriate side sills, thus relieving the tilting bars of all strain, the entire weight of the load as it is being dumped being supported by the eccentric disks D D.

Having thus described my invention, I claim and desire to secure by Letters Patent of the 55 United States—

The combination, in a drop-bottom dumping-car, of the car body or frame A, having end 60 bearing-beams, B B, bars C C, hung in said beams, and having eccentricities D D and levers F F, and bottom composed of the hinged halves E E, said eccentricities D arranged and adapted to support the bottom in both its closed and 65 open positions, so as to relieve the tilting bars from strain, substantially in the manner and for the purpose herein shown and specified.

In testimony that we claim the foregoing as our own we have hereunto affixed our signatures in presence of two witnesses.

ISRAEL SHOUDY, JR.
CHARLES ATHERTON.
